W. A. WILSON.

CUFF LINK, STUD, SOLITAIRE, TIE ORNAMENT, AND THE LIKE.

APPLICATION FILED MAR. 19, 1921.

1,390,255.

Patented Sept. 6, 1921.

INVENTOR:

W. A. Wilson

UNITED STATES PATENT OFFICE.

WILFRED A. WILSON, OF LONDON, ENGLAND.

CUFF-LINK, STUD, SOLITAIRE, TIE ORNAMENT, AND THE LIKE.

1,390,255.

Specification of Letters Patent.

Patented Sept. 6, 1921.

Application filed March 19, 1921. Serial No. 453,589.

To all whom it may concern:

Be it known that I, WILFRED AMBROSE WILSON, a subject of the King of Great Britain and Ireland, residing at London, England, have invented certain new and useful Improvements in Cuff-Links, Studs, Solitaires, Tie Ornaments, and the like; and I do hereby declare the following to be a full, clear, and exact description of the invention, such as will enable others skilled in the art to which it appertains to make and use the same.

This invention relates to an improved device for use as a cuff link, stud, solitaire and the like fastening devices of the type formed in two parts adapted to be interlocked and has for its object an improved construction of such devices which permits the parts of the device to be used as a cuff link or the like, or one part to be removed from the other to form one member of a two-part stud and if desired to enable a removable portion of one or both members to be detached and used independently as a tie ornament.

According to the invention the device is formed in two parts, adapted to be interlocked one with the other, one or each of said parts being provided with a removable plate or carrier adapted to be used separately as a tie ornament, while one or both of said parts may be utilized as part of a stud or the like.

The removable plates or carriers may each be provided with tongues, pins or pointed projections to enable the carrier to be clenched into the material of the tie or with scalloped or perforated edges to enable the same to be secured to the tie by threads or the like.

In a typical construction according to the invention, the device comprises two parts adapted to be interlocked when used as a cuff link. The one part forming a socket member is provided with a double key or other slot at one end to receive the other part forming a locking member. The locking member is provided with tongues projecting on opposite sides of its shank which tongues and shank form a snug fit in the slot of the socket member. The tongues pass into a chamber in the socket member

and their outer surfaces are provided with projecting points or spherical heads which engage a rubber or other resilient pad or radially slotted springy plate so as to frictionally retain the locking member in the locked position. 55

The outer ends of the socket and locking member have attached thereto a removable plate or carrier, which may be plain or ornamental and may be recessed or dished to receive an ornament, jewel, or the like, while the edges may be perforated or scalloped to enable the same to be secured to the material of the tie by threads or wire or the edges may be provided with tongues or pins adapted to be bent over to clench the material of the tie or to grip the outer edges of the plates or buttons pivotally connected to the outer ends of the socket and locking members. 60 65 70

The two parts with the plate or carrier attached thereto may be interlocked for use as a cuff link or the locking member may be removed and form part of a stud, the other part of which comprises a separate socket member of suitable construction and having a double key hole slot similar to the socket member of the cuff link, while if desired, the plate or carrier removably attached to one of the members may be removed and attached to a tie for use as a tie ornament. 75 80

In order that the invention may be better understood, reference is made to the accompanying drawings, in which the application of the invention to several purposes is illustrated by way of example.

Figure 1 is a sectional elevation of the two main parts of the device in the form of a cuff link and in their interlocked position.

Fig. 2 and Fig. 3 show one of the members shown in Fig. 1 in use to form one member of a two-part stud. 95

Fig. 4 is a perspective view of the end portion of socket member.

Fig. 5 is a cross sectional view on the line 5—5 Fig. 1.

Fig. 6 is a perspective view of the end of the locking member.

Fig. 7 shows both members of the device in use as a necklace or chain fastening.

Fig. 8 is a front view of the removable

carrier adapted to be attached to one or either of the members of the device or to be used separately as a tie ornament.

Fig. 9 is a sectional elevation of a modified construction.

Fig. 10 is a perspective view of a portion of the construction shown in Fig. 9.

Fig. 11 shows a modified construction as applied to a stud and

10 Fig. 12 is a detail removed from the construction shown in Fig. 11.

Referring to Figs. 1 to 6 the device consists of two parts comprising a socket member *a* and a locking member *b*. The socket member *a* is preferably formed cylindrical at *c* terminating in an eye piece *e*. The portion *c* is provided with a double key hole slot *f* extending longitudinally thereof. This slot is circular in the center and is provided with two radially disposed grooves or channels *f*¹ arranged diametrically opposite one another.

The bottom of the slot terminates in a preferably cylindrical chamber or recess *g* 25 within which is placed a pad or disk *p* of rubber or other suitable resilient material.

The locking member *b* consists of a circular shank portion *h* having at one end two tongues or projections *k* the shank and 30 tongues being of such size and shape as to form a sliding fit in the slot. The lower ends of the tongues are each provided with one or more spherical or other suitably shaped projections or pin heads *k*² which 35 when the two members are interlocked engage the surface of the resilient pad and prevent disengagement.

The end of the socket member *a* has secured thereto a plain or ornamented button, 40 disk or plate *l* preferably provided with an eye piece *m*, with which the eye piece *e* engages, thus permitting free universal movement of the disk *l*. The opposite outer end of the locking member is provided with a 45 spherical or other suitably shaped head *n*, through a hole in which passes a loop or eye *o*¹ rigidly fixed to a plain or ornamental button or the like *o*. *q* is a removable flanged plate or carrier the outer periphery of which 50 is provided with tongues or pins *q*¹ adapted to be bent over to grip the outer edges of the button *o* or the carrier may be removed from said button and used separately as a tie ornament, in which case the points *q*¹ are 55 clenched into the material of the tie, as desired. The plain or ornamental carrier *q* may be recessed or dished to receive an ornament, jewel or the like, while the edges may be scalloped and perforated as shown at 60 *q*², in Fig. 8, to enable the same to be secured to the tie or the like by threads or wire as will be readily understood.

The application of the invention to studs or solitaires is shown in Figs. 2 and 3. For 65 this purpose a separate socket member *a*¹ is

employed comprising a base portion *a*² and a shank portion *s*. The shank is formed with a double key hole slot as in Fig. 1 and with a chamber *g* for the reception of the end of the locking member *b*. The locking member is removed from the link and pressed into the shank of the stud and on being partly rotated is retained in the interlocked position by the pad of resilient material *p*. When it is desired to provide a stud of 75 somewhat shorter length the chamber *g* and the pad *p* are located in the base *s* of the stud as shown in Fig. 3.

Fig. 7 shows the two members *a* and *b* used to form a connecting member for a 80 chain or necklace. In this construction the plates *l* and *o* are removed from the ends of the members *a* and *b* respectively and the open links *t*¹, *t*² on the ends of the chain *t* are engaged with the eye piece *e* of the member *a* and with the hole in the ball *n*, at the outer end of the locking member *b*.

Referring to Figs. 9 and 10 which show a modified construction the socket member *u* comprises a hollow conical member formed 90 from sheet metal with a hollow spherical portion *u*¹ at one end. The portion *u*¹ is provided with holes or perforations to enable the plate or disk *l* to be attached thereto by means of the eye piece as shown. The locking member comprises a rod or shank portion *v*, one end of which is provided with a spherical head *v*¹ which is slightly larger in diameter than the diameter of the lipped open end *u*² of the conical member *u*. The member *u* is formed from a single piece of sheet metal, the edges abutting at *u*³ so that when the spherical head *v*¹ is forced into the open end thereof, the sides open out to permit the head to pass.

The construction of the stud according to Figs. 11 and 12 is similar to that shown in Figs. 2 and 3, with the exception that the pad *p* in the chamber *g* is replaced by a radially slotted and apertured plate *w* shown 110 separately in Fig. 12.

The plate is clamped between the base plate *a*³ of the stud and an outer cover plate *s*¹ which may be composed of a disk of ivory, bone, celluloid or any other suitable material. The plate is provided with a double-key-hole shaped aperture *w*¹ corresponding to a similarly shaped slot in the shank portion. The locking member is provided with a spherical head *k*² from which projects from diametrically opposite sides tongues or the like *k*¹ snugly fitting said double key hole slot and aperture. The plate *w* is further provided with radially disposed cuts *w*² so that when the locking member is inserted into the socket member the spherical head *k*², which is slightly larger in diameter than that of the aperture *w*¹, the sectors of the plate formed by the radial cuts are flexed so as to permit the head to 125 130 135 140 145 150 155 160 165 170 175 180 185 190 195 200 205 210 215 220 225 pass and afterward spring back to their normal position. The locking member is then partially rotated so that the two members are securely locked together.

5 It will be readily understood that the details of construction may be modified without departing from the principle of the invention, as set forth in the appended claims.

Claims:

10 1. A device for use as a cuff link, stud, solitaire, tie ornament or similar fastening device formed in two parts adapted to be interlocked one with the other, both of said parts being connected together to form a cuff link and one of said parts being removable from the other to form part of a stud, and at least one of said parts having removably mounted thereon a carrier adapted to be attached to a tie to serve as

20 a tie ornament.

2. A device for use as a cuff link, stud, solitaire, tie ornament or similar fastening device comprising a socket member having removably and pivotally connected thereto

25 at one end a plate and at the opposite end a double key hole slot terminating in a cylindrical chamber, a locking member having at one end a head formed with radial tongues forming a snug fit in the slot of

30 said socket member and adapted when partially rotated to interlock therewith and at the opposite end a removable plate, at least one of said plates having removably attached thereto a carrier provided with

35 means for attaching the same independently to a tie for use as a tie ornament.

3. A device for use as a cuff link, stud, solitaire, tie ornament or similar fastening device, comprising a socket member having

40 removably and pivotally connected thereto at one end a plate, and at the opposite end a double key hole slot terminating in a cylindrical chamber, a locking member having at one end a head formed with radial

45 tongues forming a snug fit in the slot of the socket member and adapted when partially rotated in said slot to retain the parts in the interlocked position, a detachable and pivotal disk at the opposite end of said

50 locking member, a carrier provided with means on its periphery for attaching the

same to either of the plates of the socket and locking members, and for attaching the same to a tie for use independently, as a tie ornament.

4. A device for use as a cuff link, stud, solitaire, tie ornament or other similar fastening device, comprising a socket member provided at one end with a detachable and pivotal plate, and at the opposite end with a double key hole slot terminating in an enlarged chamber, a pad of rubber within said chamber, a locking member formed at one end with a head having radial tongues forming a snug fit in said slot and chamber, spherical projections on said tongues adapted to frictionally engage said pad when the locking and socket members are interlocked, a removable and pivotal plate attached to the opposite end of said locking member, and a carrier adapted to be secured to either of said pivotal plates or to be attached to a tie for use as a tie ornament.

5. A device for use as a cuff link, stud, solitaire, tie ornament or other similar fastening device formed in two parts adapted to be interlocked one with the other, both of said parts being connected together to form a cuff link, and one of said parts being removable from the other to form part of a stud after being affixed to a tie by passing the same through a hole therein, and one end of the part attached to the tie, having removably connected thereto a carrier serving as a tie ornament.

6. A device for use as a cuff link, stud, solitaire, tie ornament or similar fastening device formed in two parts adapted to be interlocked one with the other, both of said parts being connected together to form a cuff link, each of said parts being provided at one end with a detachable and pivotal plate, and a removable carrier provided with pointed projections around its periphery adapted to be attached to either of said plates or to be clenched into the material of a tie for independent use as a tie ornament.

In testimony whereof, I have hereunto subscribed my name.

WILFRED A. WILSON.
